CONTAINER CLOSURE

Clarence M. Kastle, Cumberland, Md.

Application April 10, 1931, Serial No. 529,042

6 Claims. (Cl. 220—31)

This invention relates to improvements in container closures and has for an object to provide a closure which will effectively seal a container and which, when opened, will be maintained positively in upright position.

The invention will be fully understood from the following description taken in connection with the accompanying drawing in which latter—

10. Fig. I is a perspective view of the closure and container detached with part of the container broken away;

Fig. II is a front elevational view of the closure and container with the closure in its open position, and with part of the container broken away, and

Fig. III is a bottom plan view of the closure and the top wall of the container with the closure showing in its closed position.

20. Referring particularly to the drawing, reference numeral I designates a container having side walls 1 and an end wall 2. The end wall is provided with an opening 3 which is bounded by a flange 4 projecting outwardly from the end

25. wall at the opening. Wall 2 is provided upon its inner surface with a bead or astragal 5 which is positioned adjacent the opening. In the embodiment illustrated, the bead is formed by inserting a portion 6 of the inner surface of the wall 2. It will be understood that bead 5 can be formed by securing a flange to the inner surface of the wall 2.

A closure for the opening comprises a body portion 8 having spaced lugs 9 dependent from its periphery. The lugs are adapted to over-lie the flange 4 when the closure is in its closed position. The closure is secured in closed position by means of a wire or the like, not shown, which is passed around the closure in engage-

40. ment with the lugs and is tied in position compressing the lugs against flange 4. A resilient metallic strip 11 is secured to the inner surface of the closure at 12 and 13. Strip 11 projects beyond the periphery of the closure between two

45. adjoining lugs 9 and terminates in a hook shaped portion 14. Hook shaped portion 14 is spaced from and faces the periphery of the closure. The portion of the resilient metallic strip 11 to which the hook shaped portion 14 is attached extends from the closure on the inner side of the flange 4 and wall 2. The hook shaped portion is disposed behind the bead 5. The closure when opened and closed pivots upon the flange 4 and is secured in this position by means of the hook shaped portion of the resilient metallic strip.

When the closure is open to a position at substantially right angles to the container, the hook shaped portion is drawn tightly against the bead and further movement of the closure away from the opening is prevented. The resilient metallic strip furthermore offers yielding resistance to movement of the closure toward a closed position and as a consequence, the closure is positively maintained in a position at substantially right angles to the end wall of the container. At its opposite end the resilient metallic strip extends upwardly from the closure at 15 to form a latching device which cooperates with the inner surface of the end wall of the container adjacent the opening to secure the closure in its closed position.

By the construction described a closure is attained which can be readily detached from the container when desired. The structure is such that the closure is normally maintained in erect position when it has been opened and consequently the closure functions as a signalling agent to call attention of the operative to the fact that the closure is in open position.

Various changes may be made within the scope 80 of the appended claims in which it is desired to claim all novelty inherent in the invention as broadly as the prior art permits.

I claim:

1. In closure construction, a container having 85 an opening, a flange projecting outwardly from the container at the opening, the container having a bead on its inner surface adjacent the opening, a closure for the opening including spaced lugs depending from its periphery adapted to 90 over-lie the flange, and a resilient metallic strip secured to the inner side of the closure projecting beyond and on the inner side of the flange from the periphery of the closure between the lugs and terminating in a hook shaped portion facing and 95 spaced from the periphery of the closure and engaging the bead when the closure is opened to a position at substantially right angles to the container.

2. In closure construction, a container having 100 an opening in its wall, a flange projecting outwardly from the wall at the opening, the wall having a bead on its inner surface adjacent the flange, a closure for the opening over-lying the flange, and a resilient metallic strip secured to a 105 portion of the inner side of the closure spaced from the periphery of the cover projecting from the periphery on the inner side of the wall and flange and terminating in a hook shaped portion facing and spaced from the periphery of the 110

closure and engaging the bead when the closure is opened to a position at substantially right angles to the container.

3. In closure construction, a container having an opening, a bead on the inner surface of the container adjacent the opening, a closure for the opening, and a resilient strip secured to the inner side of the closure projecting beyond the periphery of the closure and engaging the bead when the closure is open to a position at substantially right angles to the container said strip extending across the closure and adapted to serve as a latch when the closure is in shut position.

4. In closure construction, a container having an opening, the container having a bead formed in its under surface adjacent the opening, a closure for the opening, and a resilient strip secured to the inner side of the closure projecting beyond the periphery of the closure and engaging the walls of the bead when the closure is open to a position at substantially right angles to the container.

5. In closure construction, a container having

an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

6. In closure construction, a container having an opening, a bead on the inner surface of the container adjacent the opening, a closure for the opening, and a resilient strip secured to the inner side of the closure projecting beyond the periphery of the closure and engaging the bead when the closure is open to a position at substantially right angles to the container.

7. In closure construction, a container having an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

8. In closure construction, a container having an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

9. In closure construction, a container having an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

10. In closure construction, a container having an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

11. In closure construction, a container having an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

12. In closure construction, a container having an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

an opening, a flange projecting outwardly from the container at the opening, a bead on the inner surface of the container adjacent the base of the flange, a closure for the opening and overlying the flange, and a resilient metallic strip secured to the inner side of the closure projecting beyond the periphery of the closure and engaging the bead when the closure is opened to a position at substantially right angles to the container.

13. In closure construction, a container having an opening, a bead on the inner surface of the container adjacent the opening, a closure for the opening including spaced lugs depending from its periphery adapted to overlie the container walls of the opening, and a resilient metallic strip secured to the inner side of the closure projecting beyond the periphery of the closure midway between the lugs and terminating in a hook shaped portion facing and spaced from the periphery of the closure and engaging the bead when the closure is opened to a position at substantially right angles to the container.
